(57) CLAIM

The ornamental design for a labor gown, as shown and described.

DESCRIPTION

FIG. 1 is a front perspective view of a labor gown, according to the present invention;

FIG. 2 is a front perspective view of the labor gown of FIG. 1 showing an open lower portion;

FIG. 3 is a front elevation view of the labor gown of FIG. 1 shown in an open configuration;

FIG. 4 is a rear elevation view of the labor gown of FIG. 1;

FIG. 5 is a rear elevation view of the labor gown of FIG. 1;

FIG. 6 is a front view of the labor gown of FIG. 1 shown worn by a person;

FIG. 7 is a rear view of the labor gown of FIG. 1 shown worn by a person;

FIG. 8 is a front view of the labor gown of FIG. 1 shown worn by a person; and,

FIG. 9 is a rear view of the labor gown of FIG. 1 shown worn by a person.

The broken lines in FIGS. 6 through 9 showing a standing figure depict environment and form no part of the claimed design. The remainder of the broken lines in the figure views depict stitching, which forms no part of the claimed design.

1 Claim, 8 Drawing Sheets
